CHAMPAGNE BOTTLE STOPPER

Julius H. Fessler, Berkeley, Calif.

Application June 10, 1958, Serial No. 51,288

Term of patent 14 years

(Cl. D58—10)

FIG. 1

FIG. 4

FIG. 2

FIG. 3

Figure 1 is a top plan view of a champagne bottle stopper embodying my new design.

Figure 2 is a side elevation thereof.

Figure 3 is a bottom view thereof.

Figure 4 is a section therethrough on the lines 4—4 of Figure 1.

I claim:

The ornamental design for a champagne bottle stopper, as shown.
